FIG. 1 is a front perspective view of a first embodiment of a roofing apparatus having an air blade and first linkage.

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof;

FIG. 8 is a front perspective view of a second embodiment of a roofing apparatus having an air blade;

FIG. 9 is a front view thereof;

FIG. 10 is a rear view thereof;

FIG. 11 is a top view thereof;

FIG. 12 is a bottom view thereof;

FIG. 13 is a first side view thereof; and,

FIG. 14 is a second side view thereof.

The broken lines shown represent portions of a roofing apparatus that form no part of the claimed design.
